CLAIM

The ornamental design for a closure, as shown and described.

DESCRIPTION

FIG. 1 is a top front perspective view of a closure; FIG. 2 is a top rear perspective view of the closure shown in FIG. 1;

FIG. 3 is a front view of the closure shown in FIG. 1;

FIG. 4 is a rear view of the closure shown in FIG. 1;

FIG. 5 is a left side view of the closure shown in FIG. 1;

FIG. 6 is a right side view of the closure shown in FIG. 1;

FIG. 7 is a top view of the closure shown in FIG. 1; and,

FIG. 8 is a bottom view of the closure shown in FIG. 1.

The broken lines are shown for the purpose of illustrating environmental structure and parts of the article that form no part of the claimed design.

1 Claim, 8 Drawing Sheets
